UNITED STATES PATENT OFFICE.

ROBERT SARDESON AND JOHN CORSER, OF MINNEAPOLIS, MINNESOTA, ASSIGNEES TO
ANDREW SCHARFF, OF CHICAGO, ILLINOIS.

HEATING DEVICE.

Application filed October 3, 1923. Serial No. 666,344.

To all whom it may concern:

Be it known that we, ROBERT SARDESON and JOHN CORSER, citizens of the United States, residents of Minneapolis, county of Hennepin, and State of Minnesota, have invented certain new and useful Improvements in Heating Devices, of which the following is a specification.

This invention relates more particularly to improvements in heating devices of the electrical type and includes means for obtaining a plurality of different heating values from the same unit. The selected embodiment of the invention herein shown is one specifically adapted for use with motor vehicles employing internal combustion engines and is employed to raise or maintain the temperature of the cooling medium, usually water, in the cooling system of the engines of this type. While this device may be attached to other parts of such cooling systems, it is preferably secured to the engine block. Furthermore, the device is adapted for use with the usual commercial circuits. That is, the electrical energy is preferably not taken from the usual storage battery of vehicles but is supplied from the common commercial lines such as are usually found in garages, private or public. While a number of different heats may be provided, the device is here shown as capable of a high and a low heat. For example, the low heat may be turned on during a cold night to guard against freezing of the cooling fluid, while the high heat may be turned on when it is desired to start the cooled engine or to overcome the effects of the engine having been left exposed to low temperatures without the advantage of the heating device.

The object therefore of the invention is to provide a new and improved heating device.

Other objects of the invention will more fully appear from the following description and the accompanying drawings and will be pointed out in the annexed claims.

In the accompanying drawings there has been disclosed a structure designed to carry out the objects of the invention, but it is to be understood that the invention is not confined to the exact features shown, as various changes may be made within the scope of the claims which follow.

In the drawings:

Figure 1 is a view in side elevation of an internal combustion engine with the novel device installed and showing, in vertical section, a portion of the floor and dash or instrument board;

Figure 2 is a vertical section through the heating chamber;

Figure 3 is a vertical section on the line 3-3 of Figure 2 with the addition, in vertical section, of the walls of the adjacent water-jacket portion of the cooling system;

Figure 4 is a view in front elevation of the switch mechanism as mounted upon a portion of an instrument board;

Figure 5 is a vertical section on the line 5-5 of Figure 4;

Figure 6 is a cross-section on the line 6-6 of Figure 4;

Figure 7 is a wiring diagram of the heating unit and sections; and

Figure 8 is a partial view of the opposite sides of the plug support to show the indicating means.

In this embodiment of the invention there is provided a water chamber 8, formed by the casing 9, preferably of metal. This water chamber-casing, due to the novel features and mounting thereof, may be formed of a single integral casting. This casting is shown as secured to the wall of the cooling system of an internal combustion engine and the casing is provided with one or more openings adapted to communicate with the interior of the cooling system so that there may be circulation of the water to and from the heating chamber.

The novel form of securing this heating chamber to the walls of the cooling system not only assures a secure mounting but also provides the means for the passage of the circulatory water to and from the heating chamber. As here shown, the casing 9 is provided with transversely enlarged portions 11 and 12. These are preferably disposed adjacent opposite ends of the casing and upon opposite sides of its median axis. Each enlarged portion has an opening in each of its opposite faces and these openings are aligned for the reception of the securing means. Such securing means preferably consists of a headed bolt 13 which is adapted to be passed through the aligned openings in the casing and to extend

through, and be received in threaded engagement within, the wall 14 of the cooling system. These bolts 13 effect a snug fit with the alined apertures in the casing and a packing washer 15 is preferably inserted between the bolt-head 16 and the adjacent outer face of the casing.

Communication is afforded between the cooling system and the heating chamber by means of these bolts. To that end each bolt is hollowed at its inner end and this recess 17 extends throughout its major portion but terminates short of the head of the bolt, as shown in Figure 3. Each bolt has several openings 18 cut through it substantially at right angles to the bolt, to afford free circulation between the bolt recess and the interior of the heating chamber. These hollow bolts are two in number and secure the casing adjacent its opposite ends to the wall of the cooling system.

A heating unit of the electrical type is preferably employed within this heating chamber. One end of the heating chamber is formed with an integral neck 19, the outer face of which is threaded for reception of the similarly threaded cap 21. The annular head 22 of the heating unit snugly fits within the cap 21 and against the inwardly presented shoulder of the cap which holds the head against outward movement when the cap 21 is screwed down. The cap 21 is apertured to permit passage of the sheath 23 of insulating material which carries the three wires of the heating unit.

The preferred form of heating unit consists of a base 24 of insulating material in tubular form and preferably of asbestos. The heating wire 25 is coiled about this asbestos base and a second insulating covering is laid over the heating wires. The covering preferably consists of layers 26 of mica. A metallic cylindrical shell 27, preferably of relatively thin brass, encloses the whole unit. This shell is closed at its inner end and its outer end effects a snug fit with the annular reduced portion 28 of the head 22. The outside diameter of the shell 27 is such that it makes a water-tight connection with the inner face of the neck 19 of the casing 9. Thus the water in the chamber 8 may be heated by the unit but can neither come into contact with the heating wire nor pass from the casing other than through the two circulatory passages provided by the hollowed bolts.

This heating unit is adapted to provide a plurality of heats, such for example, as a high and a low heat. This provision is simply effected by employing a terminal connected to each end of the heating wire and with a third terminal connected to an intermediate portion thereof. As is shown in the wiring diagram, Figure 7, these terminals may be of any convenient form and they are each shown as of a common type such as the

plugs 31, 32 and 33. It must be noted, however, that the plug 33 is shorter in length than the other similar plugs 31 and 32. Furthermore, it should also be noted that this relatively shorter plug 33 is connected to an intermediate portion of the heating wire. Contacts which are adapted to be connected to a suitable supply of electric energy are provided to effect engagement with these plugs so as to energize the heating wire. The contacts here shown are of the opposed finger type and the contacts 34 and 35 are of equal length and are greater than the relatively shorter contact 36.

The three plugs are mounted upon a laminated panel 37 formed of insulating material and providing an annular groove within which to receive the peripheral offset flange 38 of the recessed plate 39 adapted to be screwed to the instrument-board 41. The two similar plugs are connected by the wires 42 and 43 to the ends of the heating wire while the short plug 33 is connected by wire 44 to an intermediate portion of the heating wire. The finger contacts are preferably carried within the metallic insulated compartments provided by the head 45. The three contacts, as well as the plugs, are preferably arranged in a straight line, and the short-fingered contact 36 is joined by the connector 46 to the middle long-fingered contact 35. A main line wire 47 connects the contact 34 with a suitable source of electric energy (not shown), while the other main line wire 48 leads to the contacts 35 and 36. The outer portion of the head 45 is recessed and is closed by a cap 49 suitably secured to the head and apertured to permit passage of the main line wires 47 and 48.

In the operative use of this device, the high and low heats are obtained by a simple reversal of the connections. As the three plugs are shown as in relatively fixed position, the change is made by reversal of the finger sockets or contacts. For example, when the contacts are held in the position shown adjacent the plugs in Figure 7, they may be manually moved into engagement with the plugs. Such position will be that shown in Figure 6. The outer long contact is preferably used as the positive side of the supply line and the other long contact and its connected short contact are on the negative side. As will be noted in the drawings, the short contact does not effect electrical connection with the short plug, hence the wire 44 to the intermediate portion of the heating wire 25 is dead.

The current therefore passes through the whole heating coil or wire 25 through the end wires 42 and 43. However, when the socket is reversed, as shown in the lower part of Figure 7, all three plugs and contacts effect electrical connection because the short fingers of the contact 36 receive the

lower end portion of the outer long plug 31 and the short plug 33 is received within the long fingers of the outer contact 34. Therefore, the current passes from the positive contact to the short plug 33, line 44 to the intermediate portion of the heating wire 25 from whence it takes the two paths to the terminal wires 42 and 43 to the plugs 31 and 32 and the contacts 34 and 35. Each 10 of the two paths is about one-half of the whole wire 25 and hence a much higher heat will be developed by the increased passage of current.

As shown in Figure 8, indicating means 15 are preferably provided to indicate the operative position of the socket. For example, the letter "H" is placed upon one side of the socket and the letter "L" upon the other. Furthermore, the letter "H" is 20 preferably embossed or raised while the letter "L" is sunk so that they may be used as tactile indicating means, i. e., will give the desired indications by touch as well as by sight.

25 By the use of this novel and improved device, the water is provided with an entrance and an exit to and from the heating chamber, a plurality of heats are provided, the control of the heating device is in a convenient place upon the usual instrument-board, the hollow bolts have the double function of securing the casing in place and of providing a circulating passage for the water, the instrument-board need not be cut 30 to run the wires through as the use of the plate obviates such disadvantage, and it may also be additionally noted that the use of the compartment type of socket prevents the fingers or clips from spreading outwardly beyond proper circuit-closing limits 35 or toward short-circuiting engagements.

Having thus described our invention what we claim as new and desire to secure by Letters Patent, is:

45 1. In a heating device for the water cooling system of an internal combustion engine, the combination of a casing providing a water chamber and having a pair of aligned apertures therethrough, securing means adapted to be passed through said pair of apertures and to be secured to the wall of the cooling system, said securing means having an inner hollowed portion 50 affording communication between the water chamber and the system for inter-circulation of the water, and heating means in the chamber.

60 2. In a heating device for the water cooling system of an internal combustion engine, the combination of a casing providing a water chamber, means for securing the casing to a wall of said cooling system, heating means in the chamber, the casing and the wall having a plurality of spaced 65 intercommunicating openings whereby the

water may freely circulate to and from the water chamber.

3. In a heating device for the water cooling system of an internal combustion engine, the combination of a casing providing 70 a water chamber and having spaced pairs of aligned apertures therethrough, securing means adapted to be passed through each pair of apertures and to be secured to the wall of the cooling system, each of said securing means having an inner hollowed portion 75 affording communication between the water chamber and the system for inter-circulation of the water, and heating means in the chamber.

4. In a heating device for the water cooling system of an internal combustion engine, the combination of a casing providing a water chamber, heating means in the chamber and spaced from the inner face of the casing, the casing having openings therethrough upon opposite sides of the heating means, and securing means adapted to extend through said casing opening and the wall of the cooling system to secure the 80 casing to said wall, the securing means being adapted to afford communication between the water chamber and the system for inter-circulation of the water.

5. In a heating device for the water cooling system of an internal combustion engine, the combination of a casing providing a water chamber, heating means therein and spaced from the inner face thereof, the casing having an enlarged portion with a pair of aligned openings in the opposite sides thereof, securing means adapted to be secured in said aligned openings and to extend through the casing and the wall of the cooling system to secure the casing to 85 said wall, the securing means having a hollow portion to afford communication between the cooling system and the water chamber for inter-circulation of the water.

6. In a heating device for the water cooling system of an internal combustion engine, the combination of a casing providing a water chamber, heating means therein and spaced from the inner face thereof, the casing having enlarged portions upon opposite sides of said heating means, each enlarged portion having a pair of aligned openings in the opposite sides thereof, securing means adapted to be inserted through each aligned pair of openings and to extend 90 through the casing and the wall of the cooling system to secure the casing to said wall, each securing means having a hollow portion to afford communication between the cooling system and the water chamber for inter-circulation of the water.

7. In a heating device for the water cooling system of an internal combustion engine, the combination of a casing providing a 95 water chamber adapted to be secured to a 100

wall of the cooling system to permit inter- enclosing said covering and adapted to com-
circulation of the water between the system municate the heat of the energized wires
and the chamber, an electric heating element to said circulatory water.
in said casing, said heating element com- 10
